DeWitt LLP

(57) **CLAIM**

The ornamental design for an eyecup for an eyemask, as shown and described.

DESCRIPTION

FIG. 1 is a perspective view of an eyecup for an eyemask showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is an operational front elevation view thereof, showing two eyecups attached to a strap to form the eyemask. The broken lines shown in the drawings depict environmental subject matter that forms no part of the claimed design.

1 Claim, 8 Drawing Sheets
